DECORATIVE STAR ORNAMENT OR
SIMILAR ARTICLE

Curtis Gunter, New York, N.Y., assignor to Austen
Display, Inc., New York, N.Y., a corporation of New
York

Filed Jan. 8, 1963, Ser. No. 73,093

Term of patent 14 years

(Cl. D29—1)

FIG. 1 is an exploded view of a decorative star ornament or similar article, showing the outer part which includes the stellar arms in collapsed-stacked position;

FIG. 2 is an exploded side elevational view thereof with the two hollow hemispheres shown apart;

FIG. 3 is a perspective view, on a reduced scale, of the design of the decorative star ornament, or similar article, in the assembled position; and

FIG. 4 is a sectional view taken on the line 4—4 of FIG. 3.

This is a continuation-in-part of my application Ser. No. 71,011, filed July 23, 1962, now Patent No. Des. 195,131, dated April 30, 1963.

I claim:

The ornamental design for a decorative star ornament or similar article, substantially as shown and described.
